S. S. BRONARSKY.
COMBINED IRONING TABLE AND STEP LADDER.
APPLICATION FILED JUNE 1, 1914.

1,108,092.

Patented Aug. 18, 1914.

UNITED STATES PATENT OFFICE.

STEPHAN S. BRONARSKY, OF CHICAGO, ILLINOIS.

COMBINED IRONING-TABLE AND STEP-LADDER.

1,108,092.

Specification of Letters Patent. Patented Aug. 18, 1914.

Application filed June 1, 1914. Serial No. 842,283.

To all whom it may concern:

Be it known that I, STEPHAN S. BRONARSKY, a subject of the Emperor of Austria-Hungary, residing at Chicago, in the county of Cook and State of Illinois, have invented certain new and useful Improvements in Combined Ironing-Tables and Step-Ladders, of which the following is a specification.

This invention relates to certain new and useful improvements in a combined ironing-table and step-ladder.

An object of the invention is to provide a device capable of use both as an ironing-board and step-ladder which may be readily collapsed to assume a folded position and distended to be ready for use.

With the above general objects in view and others that will appear as the nature of the invention is better understood, the same 20 consists in the novel construction, combination and arrangement of parts to be hereinafter more fully described and then claimed.

In the accompanying drawing which 25 shows the preferred embodiments of my invention and to which reference is had herein by like characters designating corresponding parts throughout the several views:—Figure 1 is a side elevational view 30 of the device in use as an ironing board. Fig. 2 is a side elevational view of the device in use as a step-ladder. Fig. 3 is a detail plan view of one end of the board showing the iron rest. Fig. 4 is a detail 35 sectional view taken on line IV—IV of Fig. 3. Fig. 5 is a detail plan view of a portion of the opposite end of the board, and Fig. 6 is a detail perspective view of the supporting leg for the board.

40 Referring more in detail to the accompanying drawings, the reference numeral 10 designates an ironing-board which may be constructed of the usual shape and form, having pivoted to one end thereof as at 11 45 an iron rest 12 which may be swung on its pivot to the desired position to increase the plane surface of the board 10. The opposite end of the board is provided with any number of spaced openings 13 and the object 50 of these openings is to provide a steady rest for the feet of a gas stove or other object placed thereon when the device is in the position shown by Fig. 1.

When the device is to be used as an ironing-table and caused to assume the position 55 shown by Fig. 1, the ladder section is folded

as clearly shown which constitutes the support for one end of the board, while the opposite end of the board adjacent the iron rest 12 is supported by a leg 14 braced at 60 its lower end as at 15, the upper end of the leg 14 carrying a head 16 provided with a central projection 17, preferably rectangular in plan view, the rectangular projection 17 to be received within a similarly shaped 65 socket 18 formed in the under face of the board 10. The head 16 is further braced from movement relative to the board 10 by the end projections 19 engaging the sides of the board and to secure the leg 14 to the 70 board 10, hooks 20 carried by the under face of the board 10 engage the eye bolts 21 carried by the head 16.

The folded ladder section before mentioned comprises the upper and lower side 75 rails 22 and 23 being connected together by suitable spaced rungs 25. The upper side rails 22 are hingedly connected as at 26 to a head block 27 having its upper edge received in a suitably shaped socket 28 80 formed in the under face of the board 10. A hook 29 carried by one of the upper rail sections 22 engages in an eye bolt 30 carried by the adjacent ladder rung. In use as a step-ladder, it is desired that the board 10 85 which constitutes the supporting leg for the ladder and the ladder rails 22 and 23 be limited in their spacing movement and this object is accomplished by a pair of ropes 31 secured to the under face of the 90 board 10 and carrying rings 32 that engage pins 33 carried by ladder rungs 25.

The operation of the device will be clearly 95 apparent from the description of the device and the construction shown and in use as an ironing table, as shown in Fig. 1, the leg 14 held to the board 10 by the hook and eye connection 20 and 21 constitutes a support for one end of the board, while the opposite end of the board is supported by the folded 100 ladder sections 22 and 23, these sections being held in folded position by the hook and eye connection 29 and 30.

When the device is to be used as a step-ladder as shown by Fig. 2, the hook and eye connection 20 and 21 is released and the leg 14 removed from the board 10, after which the hook and eye connection 29 and 30 holding the ladder sections in folded position is released, whereupon the ladder sections will 105 be unfolded and caused to assume the position shown by Fig. 2 with the spacing ropes 110

31 engaging the ladder sections to limit the opening movement thereof.

While I have shown and described the preferred embodiment of my invention, I do not wish to confine myself to the exact details of construction shown, as various forms, modifications and arrangements of parts as shown may be had without departing from the spirit and scope of the invention as claimed.

What I claim as new is:

1. In a device of the class described, an ironing-board, a socket formed in the under face of one end thereof, a leg for supporting the socketed end of the board, a head block carried by said leg, a projection carried by said block and adapted to be received within the socket, said block carrying end projections adapted to engage the

sides of the board to prevent lateral movement thereof, and a hook carried by the board and adapted to engage the head block to hold the same in fixed relative position to said board.

2. In a device of the class described, an ironing-board, a ladder section hinged to one end thereof, said ladder section comprising a pair of foldable sections, and means carried by the board engaging the ladder section to limit the same in their opening movement.

In testimony whereof I affix my signature in presence of two witnesses.

STEPHAN S. BRONARSKY.

Witnesses:

JAMES VYCHODIL,
QUIDO PETRU.
